UNITED STATES PATENT OFFICE.

BERNHARD R. KIESSIG, OF CHICAGO, ILLINOIS, ASSIGNOR TO THE AMERICAN MUSIC COMPANY, OF CHICAGO, ILLINOIS, A CORPORATION OF ILLINOIS.

KEY-ACTION FOR MUSICAL INSTRUMENTS.

No. 853,884.

Specification of Letters Patent.

Patented May 14, 1907.

Application filed August 25, 1905. Serial No. 275,781.

To all whom it may concern:

Be it known that I, BERNHARD R. KIESSIG, a citizen of the United States, residing at Chicago, in the county of Cook and State of Illinois, have invented a certain new and useful Improvement in Key-Actions for Musical Instruments, of which the following is a specification.

This invention is particularly applicable to portable instruments wherein the strings are struck by keys somewhat after the manner of the instrument shown in Letters Patent No. 752,782, issued to me February 23, 1904.

The object of the present invention is to obtain an improved bearing for the key. I obtain this object by the mechanism illustrated in the accompanying drawings in which:

Figure 1 is a perspective view of a single key together with its hammer and mountings which embody the invention. Figs. 2 and 3 are side views of the same showing the parts in different positions. Fig. 4 is a fragmentary perspective view showing the bottom of the key and the construction of the lugs thereon.

Similar letters refer to similar parts throughout the several views.

The hammer *a* is pivoted upon the stationary bar or rod *b*, and extends in both directions therefrom. The forward portion of said hammer is the longest and carries the hammer head *a*¹ adapted to strike the respective sounding string *c* of the instrument.

The stationary rest *d* which consists preferably of felt is arranged to limit the upward motion of the keys. The rear portion of the hammer is comparatively short, as shown, and is connected by means of a link *e*, or other suitable device, to the forward extremity of the key *f*. Said key is provided with an ordinary finger piece *f*¹ at the rear extremity thereof and between its ends said

key is pivoted upon a rod or pin *g* cradled in the fulcrum piece *h*. In the preferred construction here shown, said key consists of a metallic blade vertically arranged, and the fulcrum piece consists of sheet metal bent up so as to have legs thereon and having a depression in the top thereof adapted to receive and pivotally support the rod or pin *g*. By means of this construction the rod *g* of the key merely rests upon the fulcrum piece

and is free to rise during the action of the mechanism, as will be hereinafter described. In order to prevent excessive lateral play, the fulcrum piece has slots *h*¹ at the upper portion thereof for receiving the key *f*.

Behind the fulcrum piece suitable rests *i* are provided, these being preferably covered by felt or other soft, cushioning fabric. In order to guide the key in its vertical movement said lever is provided with a lug or pin *j*², extending downwardly therefrom and adapted to fit within slots in the guide member *j*. By preference, said guide member is somewhat similar in construction to the bridge piece *h*, consisting of an approximately arched-shaped piece of metal formed from a single sheet of material. One advantage in the above described construction of the guide member *j* and fulcrum piece *h* is that they may be blanked out and formed by dies in not to exceed two operations, the resulting structure being simple, strong and durable. In front of the fulcrum piece *h*, a retractile spring *k* is mounted, one end being fastened to a suitable portion of the stationary framework *m*, and the other end being attached to the key *f* in front of the fulcrum or pivot *g*. The forward extremity of the key is connected to the hammer lever *a* at a point near the fulcrum of the latter, and in the preferred construction, the connecting link is stiff and is articulately connected to the forward extremity of the key and the rear extremity of the hammer lever. The parts are so arranged that when the key is depressed the forward extremity of the key will rise and cause the hammer head *a*¹ to descend on to the string *c* or whatever sounding member is employed. By employing a stiff link as shown, said link not only operates under tension but under compression also, thereby controlling the action of the key in both directions and rendering it possible for a single spring *k* to not only return the key to normal position but to also return the hammer head to normal or raised position away from the sounding member of the instrument. By this arrangement, in which a single spring is adequate to completely control the operation of the mechanism, it is obvious that the mechanism is simple in construction and cannot readily get out of order; moreover, the action will be complete and positive no matter in what position the instrument is held. This

feature however relates more particularly to a key action and is not claimed herein, this being the subject of a separate application filed by me February 3, 1906, Serial No. 5 299,336.

The damper *o* which consists of felt or other suitable material, is carried upon the damper arm *o*¹ which in the preferred construction is directly attached to the key lever *f* at a point in front of the pivot or fulcrum thereof. In the best construction, here shown, said damper lever consists of a flat piece of metal having some resiliency and being so formed that at least the lower portion 15 of said arm is adapted to yield in a direction toward and from the sounding member *c*. This, too, is an advantageous feature of my device, for by it the damper arm is practically of a single piece with the key lever and 20 there are no joints or connections which are liable to get out of order.

In operation, when the key *f*¹ is depressed the forward extremity of the key lever rises and causes the hammer head *a*¹ to be lowered 25 toward the sounding member *c*. The parts are so constructed, however, that the key *f*¹ contacts the rests *i* before the hammer head reaches the sounding member, that is, when 30 the hammer head is in the position shown in dotted lines, Fig. 2. If the key were lowered very slowly the hammer head would never reach the sounding member, but the necessary overthrow, which must take place in the normal operation of a mechanism of this 35 class, is provided for by the cradle construction of the pivot of the key levers, for by reference to Fig. 3, it will be seen that the pivot *g* is permitted to rise to a slight distance out of its bearing in the fulcrum piece *h*, thereby 40 permitting the final or overthrow movement of the hammer head. As soon as this overthrow has taken place the retractile spring *k* draws the key lever down to a bearing and thereby raises the hammer again to the position 45 shown in dotted lines, Fig. 2. As long as the key remains depressed, the damper *o* will remain lifted away from the sounding member *c* and permit the same to prolong its sound, and yet by means of the arrangement 50 shown, the hammer, as soon as it has struck the sounding member, will rise therefrom sufficiently to not interfere with the vibration of the sounding member.

What I claim as new and desire to secure 55 by Letters Patent is:

1. In a key action the combination of a hammer, a key articulately connected thereto for operating the same, a fulcrum pin fixed with reference to said key, and a fulcrum

piece for pivotally supporting said pin, said 60 fulcrum piece having a depression formed in the upper portion thereof wherein said pin rests.

2. In a key action the combination of a hammer, a key articulately connected thereto for operating the same, a fulcrum pin fixed with reference to said key, and a fulcrum piece for pivotally supporting said pin, said 65 fulcrum piece having an open depression formed in the upper portion thereof wherein 70 said pin rests.

3. In a key action, the combination of a hammer, a key, a fulcrum pin which is fixed with reference to said key, a fulcrum piece having a depression in the top for cradling 75 said pin, and connections between said hammer and said key whereby when the key is depressed, the resistance of the hammer tends to press the fulcrum pin down into said depression in the fulcrum piece. 80

4. In a key action, the combination of a hammer, a key connected thereto for operating the same, a key rest for limiting the downward movement of said key, a fulcrum pin in said key, and a fulcrum piece having a 85 depression for supporting said pin, said depression being open at the top whereby the key is permitted to rise and lift said pin from its seat during the overthrow period of the hammer. 90

5. In a key action, the combination of a key, a fulcrum pin and a fulcrum piece for pivotally supporting said fulcrum piece consisting of sheet metal bent up so as to have supporting legs formed thereon and a depression in the top for supporting said pin, whereby the pin is cradled in the fulcrum piece and is prevented from horizontal movement transverse to its axis. 95

6. In a key action, the combination of a key, a fulcrum pin, and a fulcrum piece for pivotally supporting said pin, said fulcrum piece consisting of a single piece of sheet metal bent into such form as to have supporting legs formed integral therewith and a 105 depression located in the upper portion of the fulcrum piece for cradling said pin, and said fulcrum piece having slots in its upper portion running transverse to said depression for receiving and guiding the key. 110

In witness whereof, I have hereunto subscribed my name in the presence of two witnesses.

BERNHARD R. KIESSIG.
